US00D898925S

(12) **United States Design Patent** (10) Patent No.: **US D898,925 S**
(45) Date of Patent: **** Oct. 13, 2020**

(54) **MEDICAL DRESSING**(71) Applicant: **Smith & Nephew PLC**, Watford, Hertfordshire (GB)(72) Inventors: **William Kelbie**, Inverness (GB); **Reece Knight**, Kingston upon Hull (GB); **Daniel Lee Steward**, Kingston upon Hull (GB)(73) Assignee: **Smith & Nephew PLC**, Watford (GB)(**) Term: **15 Years**(21) Appl. No.: **29/663,288**(22) Filed: **Sep. 13, 2018**(51) LOC (12) Cl. **24-04**

(52) U.S. Cl.

CLAIM

The ornamental design for a medical dressing, as shown and described.

DESCRIPTION

FIG. 1 is a front view of a label for a medical dressing, showing my new design.

FIG. 2 is a top, right-side, and front perspective view of a medical dressing.

FIG. 3 is a top plan view of the medical dressing of FIG. 2. FIG. 4 is a bottom plan view of the medical dressing of FIG. 2.

FIG. 5 is a right side elevation view of the medical dressing of FIG. 2.

FIG. 6 is a left side elevation view of the medical dressing of FIG. 2.

FIG. 7 is a front elevation view of the medical dressing of FIG. 2.

FIG. 8 is a rear elevation view of the medical dressing of FIG. 2.

FIG. 9 is a top, right-side, and front perspective view of a second embodiment of a medical dressing.

FIG. 10 is a top plan view of the medical dressing of FIG. 9.

FIG. 11 is a bottom plan view of the medical dressing of FIG. 9.

FIG. 12 is a right side elevation view of the medical dressing of FIG. 9.

FIG. 13 is a left side elevation view of the medical dressing of FIG. 9.

FIG. 14 is a front elevation view of the medical dressing of FIG. 9.

FIG. 15 is a rear elevation view of the medical dressing of FIG. 9.

FIG. 16 is a top, right-side, and front perspective view of a third embodiment of a medical dressing.

FIG. 17 is a top plan view of the medical dressing of FIG. 16.

FIG. 18 is a bottom plan view of the medical dressing of FIG. 16.

FIG. 19 is a right side elevation view of the medical dressing of FIG. 16.

FIG. 20 is a left side elevation view of the medical dressing of FIG. 16.

FIG. 21 is a front elevation view of the medical dressing of FIG. 16.

FIG. 22 is a rear elevation view of the medical dressing of FIG. 16.

FIG. 23 is a top, right-side, and front perspective view of a fourth embodiment of a medical dressing.

FIG. 24 is a top plan view of the medical dressing of FIG. 23.

FIG. 25 is a bottom plan view of the medical dressing of FIG. 23.

FIG. 26 is a right side elevation view of the medical dressing of FIG. 23.

FIG. 27 is a left side elevation view of the medical dressing of FIG. 23.

FIG. 28 is a front elevation view of the medical dressing of FIG. 23.

FIG. 29 is a rear elevation view of the medical dressing of FIG. 23.

FIG. 30 is a top, right-side, and front perspective view of a fifth embodiment of a medical dressing.

FIG. 31 is a top plan view of the medical dressing of FIG. 30.

FIG. 32 is a bottom plan view of the medical dressing of FIG. 30.

FIG. 33 is a right side elevation view of the medical dressing of FIG. 30.

FIG. 34 is a left side elevation view of the medical dressing of FIG. 30.

FIG. 35 is a front elevation view of the medical dressing of FIG. 30; and,

FIG. 36 is a rear elevation view of the medical dressing of FIG. 30.

The broken lines in the figures depict portions of a medical dressing and form no part of the claim.
